UNITED STATES PATENT OFFICE.

FRANK E. BLANCHARD, OF CHICAGO, ILLINOIS.

FINGER-NAIL BUFFER MEANS.

Application filed August 1, 1925. Serial No. 47,461.

This invention aims to provide a means by which the finger nails may be easily, quickly, and thoroughly buffed and polished.

The common practice by manicurists is to buff and polish the nails by means of an elongated buffing and polishing pad which is reciprocated rapidly across the tops or faces of the nails. As these tops or faces are convex, the greatest amount of polishing is done on the center or tops of the nails while a very considerable portion of the nail surface about its edges lies below the plane of the adjacent cuticle and cannot therefore be reached by the buffing pad or satisfactorily polished. In the effort to polish the edges so far as it is possible at present, the manicurist must bear down heavily upon the buffing pad and reciprocate it across the cuticle adjacent to the edges of the nail. This polishes the cuticle as well as the nail and cannot be avoided by the most skillful use of the buffing pad, while the heat developed by the friction of the pad tends to burn or accumulatively callous the adjacent cuticle, thus necessitating further trimming, removal, or treatment of the same which is undesirable as it promotes further cuticle growth. In addition, when the nails are frequently manicured, excessive polishing with the usual means makes the center of the nails very thin and causes the formation of unsightly ridges, bulges, or hollows. An additional objection to the buffing pad when used professionally is that the nails of a great many people are polished with the same pad which is unsanitary.

One of the primary purposes of my present invention is to provide a means by which nails may be buffed and polished throughout their entire areas and around the margins of the nails as well as in the center, thus producing a uniform polish over the entire area of the nail.

Another object is to provide a means which will preclude injury or staining by the buffing or polishing tool to the cuticle surrounding the nail.

A further object is to provide a machine which will be light in weight so that it can be readily handled by the operator, one which will provide a plurality of polishing tools or pads, one to be used with buffing material and the other with polishing material, and also to provide a machine which

can be economically manufactured and will be durable in use and which will comprise replaceable buffing and polishing pads and replaceable cuticle guards or protectors so that fresh pads and sterile protectors can be used upon each person, thus making the device thoroughly sanitary.

Other objects and advantages of my invention will be readily appreciated when the same becomes better understood by reference to the following description when considered in connection with the accompanying drawing.

Referring to the drawing:

Fig. 1 is a side elevation, partially in section, of a buffing machine embodying my invention,

Fig. 2 is a fragmentary enlarged sectional view showing one of the tools and protectors,

Fig. 3 is a similar view showing a modified form of cuticle protector,

Fig. 4 is a view of an optional form of replaceable polishing tip, shown in contact with a finger nail, and

Fig. 5 is a fragmentary cross-sectional view showing the manner in which the oscillatory shaft is driven.

Referring to the drawing, reference character 5 indicates generally an electric motor sufficiently small to be grasped and carried by the hand of the user. Current is supplied to this motor in the usual manner through a conductor carrying cable 6. The end plate 7 for one end of the motor is equipped with an outwardly projecting housing 8 which is illustrated in Fig. 1 as being provided with oppositely extending bearings 9 and 11 respectively, in which is journaled a shaft 12.

The motor shaft 13 which projects axially into the housing 8 is connected to the shaft 12 for the purpose of driving the same, and while a bevelled or worm gear or other connection between these shafts may be employed to impart to the shaft 12 a continuous rotary movement, I have shown a practical method whereby satisfactory results are obtained by oscillating rather than rotating the shaft 12, and in Fig. 1 I have illustrated a preferred connection between these shafts for effecting this movement. The motor shaft 13 is therefore provided with an eccentrically disposed driving stud 14 which may be secured to the shaft in any suitable manner, but is herein illustrated as

being seated in a socket formed in a collar 15 which is fixed to the shaft 13 by a set screw 16. The projecting end of the stud 14 projects into a longitudinal groove 17 formed in a collar 18 secured to the shaft 12 by a set screw 19. This whole assembly is inclosed and protected by a removable cap 21 fitting over the outer end of the casing 8.

The stud 14, as it rotates with the motor shaft 13, reciprocates in the groove 17 of the collar 18 and imparts to this collar and to the shaft 12 to which the collar is fixedly secured, a rapid oscillatory movement. The tool or tools, which will be later described, carried by the shaft 12, therefore partake of an oscillatory movement which I have found to be quite satisfactory in accomplishing the desired results. I do not confine myself to motor drive for this purpose, however, as the oscillatory movement of the tool or tools can very well be supplied by a flexible shaft operating from a distant source or by means of an electromagnetic vibratory device mounted on or mechanically connected to the shaft 12 so that the oscillatory movement will be supplied substantially as previously described. I illustrate the motor drive however as a preferable means of operation.

Referring now to Fig. 2, it will be observed that that portion of the shaft 12 projecting beyond the bearing 9 comprises a reduced portion 22, and its outer end preferably, although not necessarily, is provided with a cushion 23 in the form of a piece of rubber or other suitable material. Around the end of the shaft there is disposed a tip indicated generally by reference character 24, which consists of a piece of suitable buffing and polishing material such as chamois skin which is wrapped over the end of the shaft 12 and is secured to the shaft by wrapping a cord or string 25 around the tip where it surrounds the reduced portion 22 of the shaft 12. A rubber band or other securing means might be employed if preferred.

An optional construction is illustrated in Fig. 4, wherein a cap 30 of metal, rubber, or other suitable material slips tightly over the end of shaft 12 so that it will partake of any motion of the shaft. A small disc or tip of a suitable buffing or polishing material such as chamois skin, cork, felt, or leather 24 is firmly attached or cemented to the end of the cap 30 thus providing a means whereby the minimum of such buffing or polishing material is employed and the whole can be quickly attached or detached. I do not confine myself to any particular buffing or polishing material for this means or purpose however or to any means of attaching the tool or tip to the shaft 12 but claim any means for achieving this end when attached to a rotating or oscillating

shaft 12, so that the exposed end or tip will buff or polish the nail.

In order to prevent burning, abrasion, or injury of the cuticle at the edge of the nail by the rapid movement of the side walls of the tip 24, my invention contemplates the provision of a protector, guard, or shield 26, which will preclude contact of the side walls of the tip 24 with the cuticle. The form of guard shown in Fig. 2 comprises a cylindrical member 26 made of any suitable material but preferably of a non-metallic nature such as celluloid or fiber. This protector is adapted to slip over and snugly fit the perimeter of bearing 9 while its other end is reduced in diameter to closely approach the side walls of the buffing or polishing tip 24. While there is normally some space between the tip 24 and the protector 26, it is evident that in operation this space may become filled with excess buffing or polishing powder or the pressure of tool on the nail and against the edge of the cuticle may force the tip 24 and the protector 26 together. Either of these conditions will result in wearing away the protector material 26 and it is evident that the material so worn away can easily deposit in the joint between the nail and the cuticle. As this must be washed or cleaned out it is apparent that the protector material should preferably be of a non-metallic nature and of a light color so that the surrounding cuticle or tissue will not be indelibly stained or left in an unsightly condition.

The protector is removable for cleaning or other purposes and may be readily slipped off when desired and the tip 24 can be readily detached from the shaft 12 after the removal of the protector. Both the tip and the protector, therefore, are readily removable and replaceable so that a fresh tip and a clean or sterile protector may be used for each person, thereby making the device entirely sanitary.

In Fig. 3 I have illustrated a modified form of protector which consists of a sleeve 27 of celluloid, fiber, or other suitable smooth material adapted to be slipped over and to snugly fit the side walls of the tip 24. In this instance, the protector will, of course, partake of the movements of the tip, but since it presents a smooth exterior, it may be pressed against the cuticle at the sides of the nail without injury to the cuticle.

While the machine may be so constructed that the shaft 12 will project at one side only of the casing 8, and the machine will have but one tool or tip, I prefer that it be equipped with a plurality of tools which may be of various sizes, but in practice, when adapted to be used with different buffing or polishing compounds, I prefer that the tips be made of different material.

In the form shown in Fig. 1, the tip 28, at the opposite end of the shaft and tip 24, is preferably made of a rougher or harsher material than that used on the tip 24, so that 5 it can be employed in removing stains from the nails and also from the fingers, if desired. The tool 28 may also be larger or, if preferred, smaller than the tip 24, and the guard or protector 29 will be of corresponding dimensions.

In the use of a machine embodying my invention, the tip to be employed is dipped in the polishing or buffing material and while being oscillated by the rapidly revolving 15 motor, is traversed over the nail under such pressure as the manicurist may deem necessary to apply. The tip, being relatively small, is capable of being moved over the entire surface of the nail and close 20 to the edges thereof, and all danger of injury to the surrounding cuticle is obviated by the cuticle protector surrounding the tip, and which may be moved into intimate contact with the cuticle without injury thereto.

25 While I have shown and described a preferred embodiment of the invention, the structural details may obviously be varied within considerable limits without departing from the essence of the invention as defined in the following claims.

I claim:

30 1. In a finger nail buffing machine having operating means, an end buffing tool carried by said means, and means surrounding said tool for protecting the cuticle around said nail during the buffing thereof.

35 2. In a finger nail buffing machine having operating means, an end buffing tool carried by said means, and stationary tubular means for protecting the cuticle of the nail from injury by said tool.

40 3. In a finger nail buffing machine having an operating shaft, an end buffing tool carried thereon, and stationary tubular means surrounding said shaft for protecting the cuticle of the nail from injury by said tool.

45 4. In a finger nail buffing machine, the combination with an operating member, an

end buffing tool carried by said member, and stationary tubular means for protecting the 50 cuticle of the nail from injury by said tool.

5. In a finger nail buffing machine, the combination with an operating member adapted to be oscillated, an end buffing tool carried by said oscillating means, and stationary tubular means for protecting the 55 cuticle of the nail from injury by said tool.

6. In a machine of the character described, the combination of an operating member, a plurality of end buffing tools carried by said 60 operating member, and a stationary tubular protector for preventing injury to the cuticle of the nail by a tool.

7. In a machine of the character described, the combination of an operating 65 member, a plurality of operatively connected and oppositely disposed end buffing tools removably connected with said operating means.

8. In a machine of the character described, the combination of an operating member, means carried by said operating member and having a removable end buffing tip attached thereto, and a stationary tubular removable cuticle protector surrounding 75 the said walls of said means.

9. In a finger nail buffing machine having operating means, an end buffing tool operatively connected to said means, and means surrounding said tool for protecting the 80 cuticle around said nail during the operation thereof, and a secondary tool operatively associated with the said operating means.

10. A finger nail buffing machine having 85 operating means, an end buffing tool carried by said means, and means surrounding said tool for protecting the cuticle around said nail during the buffing thereof, and a secondary tool attached to said operating 90 means and movable simultaneously with the said buffing tool.

In witness of the foregoing I affix my signature.

FRANK E. BLANCHARD.
